UNITED STATES PATENT OFFICE.

WILLIAM A. BRAMLETTE AND WILLIAM H. EVANS, OF BONHAM, TEXAS.

COPY-HOLDER.

SPECIFICATION forming part of Letters Patent No. 508,863, dated November 14, 1893.

Application filed August 18, 1893. Serial No. 483,464. (No model.)

To all whom it may concern:

Be it known that we, WILLIAM A. BRAMLETTE and WILLIAM H. EVANS, citizens of the United States, residing at Bonham, in the 5 county of Fannin and State of Texas, have invented certain new and useful Improvements in Copy-Holders; and we do hereby declare the following to be a full, clear, and exact description of the invention, such as will enable others skilled in the art to which it 10 pertains to make and use the same, reference being had to the accompanying drawings, and to letters of reference marked thereon, which form a part of this specification.

15 Our invention relates to an improved copy-holder, more especially designed for type-writing machines, of any of the prevalent forms, and it has for its object to facilitate the holding of the copy; also to aid the reader 20 or operator to readily retain his "place," in reading the copy line by line, in the usual way, to insure accuracy in copying the same; also to provide for its adaptation to the machine, irrespective of the size of the latter; 25 and the invention consists of the novel combination and arrangement of parts, including their construction, substantially as hereinafter more fully disclosed and pointed out in the claims.

30 In the accompanying drawings—Figure 1 is a side elevation of our improved copy-holder for type-writing machines, as applied for use. Fig. 2 is a broken, partly sectional view of the same, and Fig. 3 is a transverse section 35 of the copy-holder proper.

In the embodiment of our invention, we provide a case or closure A open at its rear side, preferably, consisting of a base α , end-portions α' secured to said base, a curved 40 metal top-portion α^2 , secured upon said end portions as shown, among other ways, and the similar front portion α^3 , anchored, or otherwise secured, in said base, and having its upper edge standing slightly, or a short distance, away from the lower front edge of the top-portion α^2 , thus providing a slot or opening α^4 , therat, for the passage therethrough of the paper or copy, as indicated in dotted lines, in Fig. 3.

45 Arranged within the closure or casing A, are the paper or copy feeding rolls b , the

paper or copy being passed and held, therebetween, said rolls being mainly of wood and covered preferably with rubber for the purpose, as well understood, of producing the 55 requisite friction to aid the feeding of the interposed paper or copy as the rolls are actuated or turned. The journals of these rolls bear in slots b in the end-portions α' , of the case or closure A, the upper journals having 60 follower-blocks c resting thereon, and upon these blocks or followers is exerted the action of springs d held in place, and whose tension can be regulated, by set or adjusting screws e , in regulating the frictional contact 65 between the rolls and paper or copy. One of the journals of the upper roll is provided with a milled disk or thumb-piece f to provide for the turning or actuation of the rolls in feeding the paper or copy therebetween, 70 at the convenience of the operator or reader. The straight-edge, upper portion of the front-plate α^3 , serves, it will be seen, as a guide for the eye of the operator in reading the copy, just as each line of matter emerges from behind, and is stopped just above, said straight-edge by accordingly controlling the movement of the rolls, the next or succeeding line 75 of the copy remaining, in the mean time, unexposed.

To provide for adjustably supporting the case or closure A in an elevated position and conveniently to the operator or reader, legs or standards C C, having upper right-angled portions C' C', are employed, said right-angled portions C' C' having slots c' therein, through which are inserted adjusting or set screws c^2 adjustably connecting the legs to said case. The legs or standards when extended as indicated in dotted lines, in Fig. 1, 85 rest upon the floor, but when constructed as shown in full lines, they have connected to them the angle-arms C² of brackets G' adapted, preferably as shown, for connection to the base of the type-writer, they being provided with set or holding screws g for that purpose.

The legs or standards C and the arms C² of the brackets G' are provided with longitudinal slots c^3 , c^4 , respectively; and engaging 90 the slots are set or holding screws C³, to provide for the requisite adjustment of the parts

to accommodate the copy-holder to the convenience of the operator.

The arms C², are adjustably connected together by the sectional cross-bar consisting 5 of the sections D, D, one having a set screw d' engaging a slot d², in the other section to provide, with the set screw and slot arrangement c' c², aforesaid, for the accommodation or adjustment of the parts or legs and brackets to different sized machines.

Having thus fully described our invention, what we claim, and desire to secure by Letters Patent, is—

1. The combination, with a copy-holder, of 15 the legs or standards having right angled upper end-portions provided with slots and adjusting screws engaging said slots and connecting said upper end-portions to the case of the copy-holder, substantially as specified.
2. The combination, with a copy-holder, of 20

the legs or standards having adjustable connection with the case of said copy-holder and connected together by a cross bar consisting of adjustable section, substantially as set forth.

3. The combination, with a copy holder, of 25 the legs or standards connected thereto and having longitudinal slots, and the brackets adapted to a type-writer, and having angularly disposed arms provided with longitudinal slots, and adjusting screws engaging the slots of said legs or standards and the arms of said brackets, substantially as set forth.

In testimony whereof we affix our signatures in presence of two witnesses.

WM. A. BRAMLETTE.
WILLIAM H. EVANS.
